UNITED STATES PATENT OFFICE.

ALONZO GRIGGS, OF CHARLESTON, SOUTH CAROLINA.

AIR-HAMMER.

1,172,206.

Specification of Letters Patent. Patented Feb. 15, 1916.

Application filed April 10, 1915. Serial No. 20,519.

To all whom it may concern:

Be it known that I, ALONZO GRIGGS, a citizen of the United States, residing at Charleston, in the county of Charleston and State of South Carolina, have invented new and useful Improvements in Air-Hammers, of which the following is a specification.

The invention relates to an improvement in air hammers and particularly to a construction for holding in the snap and plunger, with relation to the barrel of a pneumatic hammer.

The present improvement involves a cuff member arranged for coöperation with nuts mounted for adjustment on the snap and on the barrel and adapted to receive and support the cuff, the latter limiting the play of the snap.

The invention will be described in the following specification, reference being had particularly to the accompanying drawings, in which:

Figure 1 is a perspective view showing the improved structure; Fig. 2 represents perspective details of the three parts of the structure.

Referring particularly to the accompanying drawings wherein is shown sufficient of an air hammer to illustrate the application as to the improvement, 1 represents the usual barrel and 2 the snap or plunger. In carrying out the present invention it is to be understood that aside from the particular details, hereinafter noted, the parts just enumerated are of any usual or preferred construction.

For the purposes of the present invention the barrel is provided with a sleeve extension 3 to receive the operative end of the snap, the latter being also formed with a cylindrical enlargement 4 corresponding in external diameter to that of the sleeve. The cuff 5 is formed to present two cylindrical heads 6 and 7, of duplicate structure, which at their respective upper and lower portions have lateral projections 8 which beyond the plane of the cylindrical portions of the head are connected by an extension 9. As thus constructed the cuff presents an integral member including a side portion having at the respective ends heads which in part, that is in the portions projecting toward

each other, present comparatively free cylindrical portions. Duplicate nuts 10 and 11 are arranged for coöperation with the sleeve 55 portion 3 of the barrel and the enlargement 4 of the snap. These nuts being adapted for threaded connection with the parts described and having cylindrical enlargements forming in effect sleeve extensions 12 to receive the free portions of the cuff, the nut 10 being arranged upon the extreme end of the barrel, and in part spaced therefrom, will as is obvious permit a limited longitudinal movement of the snap and its holder 60 relative to the barrel, the remaining attached parts serving to positively prevent accidental removal of the snap from the barrel.

In use the cuff is first applied over the 70 sleeve portion of the barrel, and a nut applied thereto with the cylindrical enlargement thereof to receive the cylindrical portion of the cuff. The second nut is then applied to the cylindrical portion of the upper 75 portion of the cuff and the snap passed downwardly therethrough and threaded into the nut, the upper nut in this position receiving the cylindrical portion at the upper end of the cuff, the construction permits 80 a limited longitudinal movement of the snap and holder while the snap is prevented from accidental disconnection from the barrel. The cuff as an entirety is freely rotatable about the snap so that it may be adjusted to 85 any position so that it will be out of the way of the operator.

The improvement provides a means for the purpose described which will not heat and will not become separated as the ordinary spring, heretofore used for the purpose, is liable to do in use.

What is claimed is:

1. The combination with a pneumatic hammer including a barrel having a reduced and threaded end and a snap having a threaded end, of a cuff including opposite cylindrical heads to slidably receive the ends of the snap and barrel and a plate extension rigidly connecting the heads and means having threaded connection with the snap and barrel and slidably receiving the heads of the cuff. 95

2. The combination with a pneumatic

hammer including a barrel having a reduced and threaded end and a snap having a threaded end, of a cuff including opposite cylindrical heads to slidably receive the ends of the snap and barrel and a plate extension rigidly connecting the heads and nuts threaded upon the ends of the snap and barrel, said nuts having portions of in-

creased diameter to slidably receive the heads of the cuff.

In testimony whereof I affix my signature in presence of two witnesses.

10

ALONZO GRIGGS.
